[57] **CLAIM**

The ornamental design for a grommet for use in a metal stud, as shown and described.

DESCRIPTION

FIG. 1 is a top, right side perspective view of the grommet of the present invention showing my new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The bottom view of the grommet of the present invention is a mirror image of the top view of FIG. 5.
